UNITED STATES PATENT OFFICE.

AMOS F. CHASE, OF LYNN, MASSACHUSETTS.

ROMPERS.

1,307,959.

Specification of Letters Patent. Patented June 24, 1919.

Application filed April 7, 1919. Serial No. 288,004.

To all whom it may concern:

Be it known that I, AMOS F. CHASE, citizen of the United States, residing at Lynn, in the county of Essex and State of Massachusetts, have invented certain new and useful Improvements in Rompers; and I do declare the following to be a full, clear, and exact description of the invention, such as will enable others skilled in the art to which it appertains to make and use the same.

My invention has for its object to provide a child's romper which may be easily and inexpensively manufactured, principally from a single length of material, and with this object in view, the invention resides in the novel features hereinafter described and claimed, reference being made to the accompanying drawings.

Figure 1 is a perspective view showing the front of the garment.

Fig. 2 is a perspective view showing the back of the garment.

Fig. 3 is a detail section on the plane indicated by the line 3—3 of Fig. 2.

Fig. 4 is a plan view of the length of material of which the garment is formed.

Figs. 5 and 6 are perspective views looking at the back of a different form of garment.

Fig. 7 is a detail section on the plane of the line 7—7 of Fig. 5.

In the manufacture of the garment, I provide a single length of material 1 having near one of its ends 2, a neck opening 3, while adjacent its other end 4, the length of material is provided with notches 5 to receive the child's legs. Opposite the neck opening 3, the length of material may be provided with projections 6 to form short sleeves.

From the opening 3, the end 2 extends downwardly to form the upper half of the garment back; the intermediate portion of the material constitutes an interrupted front for the garment; and the end 4 extends upwardly from the notches 5 to form the lower half of the garment back. This half is of greater width than the upper half 2 in order that it may be readily dropped when necessary, and normally the upper edge of said lower half is gathered around the body by a draw-string 7 located in a hem 8 with its

ends secured in the side seams 9 by means of which the front and back of the garment are stitched together from the notches 5 to 55 points below the shoulders, leaving armholes 10. If desired, a tab 11 and button 12 may be provided to prevent separating of the upper and lower halves of the garment back. However, if these parts are eliminated, it 60 will be seen that no buttons whatever are necessary, this being of great advantage not only in the manufacture of the garment, but in laundrying the same.

If desired, a strip of material 13 may be 65 stitched around the edge of the neck opening 3 and provided with a draw-string 14 for gathering it around the neck after the child has inserted its head through said opening.

In the form of the invention shown in Figs. 5, 6 and 7, all parts are the same as above described except that the lower end of the upper back half 2 depends freely over the upper portion of the lower half and is 75 provided with an internal hem 15 and a draw-string 16. The ends of the two strings 16 and 7 are adapted to be tied together after the garment is gathered around the child's body, thus rendering the use of a tab and 80 button unnecessary.

From the foregoing, taken in connection with the accompanying drawings, it will be seen that although both forms of the invention are of extremely simple and inexpensive 85 formation, they will be highly desirable, and since probably the best results are obtainable from the details disclosed, they may well be followed. However, within the scope of the invention as claimed, numerous minor 90 changes may well be made. Double faced goods may be used if desired and the garment thus made reversible.

I claim:

1. A romper formed principally of a single length of material having a neck opening cut near one end, said end depending from said opening and forming the upper half of the garment back, the remainder of said length forming the complete garment 95 front, having notches to receive the legs, and extending upwardly from these notches to form the lower half of the garment back, the edges of the front and back being 100

stitched together from said notches to points below the shoulders, leaving armholes; the width of said lower half of the back being greater than said upper half and having a draw-string.

2. A structure as specified in claim 1, together with an internal hem on said upper half of the garment back, and an additional

draw-string therein adapted to be tied with the aforesaid draw-string.

In testimony whereof I have hereunto set my hand.

AMOS F. CHASE.
